EDWARD N. TRUMP, OF SYRACUSE, NEW YORK.

PROCESS OF EVAPORATING LIQUOR.

SPECIFICATION forming part of Letters Patent No. 743,352, dated November 3, 1903.

Application filed March 10, 1903. Serial No. 147,165. (No specimens.)

To all whom it may concern:

Be it known that I, EDWARD N. TRUMP, a citizen of the United States, residing at Syracuse, in the county of Onondaga and State of New York, have invented a new and useful 5 Process of Evaporating Liquor, of which the following is a specification.

My invention relates to improvements in the process of evaporating liquors, and is especially useful in connection with the evaporation of liquors in which crystals form.

The object of my new process is to enable liquor to be evaporated under vacuum-pressure, but so that the crystals which form in such liquor shall not be allowed to settle and become caked. I accomplish this object by maintaining a circulation of that portion of the liquor only which is richest in crystals—that is, the portion of the liquor which has 15 been subject to the evaporating operation—and I maintain this circulation in such a manner that the richer or crystal-bearing liquor is circulated from and back to the vacuum-pan without being dissipated through the 20 poorer or unevaporated liquor. I maintain this circulation in such a way that the crystals will be barely suspended in a minimum quantity of liquor—that is, a quantity of liquor barely sufficient to support or make possible 25 the circulation. I maintain this circulation from the pan back to the pan past a valve-controlled exit, so that the crystals may be withdrawn from time to time without interfering with the evaporating process—that 30 is, so that the evaporating and circulating process is a continuous one and is not interfered with by the intermittent or arbitrary withdrawal from time to time of crystal-bearing liquor.

40 This process may be accomplished in connection with an apparatus, for example, such as is made the subject of a separate application having Serial No. 50,932, filed March 13, 1901, and is shown in the accompanying drawings, in which—

45 Figure 1 is an elevation of my device with a part of the pan broken away to show the interior arrangement. Fig. 2 is a plan view of the under side of the pump and grinder, and Fig. 3 is a vertical section on line 3 3 of Fig. 2.

Similar numerals refer to similar parts throughout the several views.

The vacuum-pan 1, connected with condenser 18 and suitable air-exhaust means and provided with steam-heating pipes 2, may be of any form usually employed for evaporation of liquors and the production of crystals. Steam is introduced into the pipes 2 for the purpose of raising the temperature of 55 the solution to induce evaporation, the water evaporated passing over to the condenser while crystals form and drop through the liquor into the bottom of the pan 1.

Communicating with the bottom of the pan 60 1 is the receiver 3. The opening between said receiver 3 and pan 1 is controlled by the valve 4, which is operated by valve-wheel 5. This valve is adapted when desired to close communication between vacuum-pan 1 and receiver 3. During the operation of the device the valve 4 is kept open, and the crystals descending by their superior specific gravity into said receiver 3 would soon fill it and the pipe leading therefrom to the grinder 6 and 65 pump 7 (displacing a large amount of the liquor which rises into the vacuum-pan above) and, if undisturbed, would soon become hard and could only with difficulty be drawn off at the bottom. To prevent the undue accumulation 70 of crystals in the receiver 3, a circulatory system is provided, as follows: A pipe leading from the bottom of the receiver 3 connects the receiver with the centrifugal pump 7, which discharges into the pipe 8, which extends 75 upwardly to a distance considerably above the level of the liquor in the vacuum-pan, where it discharges into the chamber 16—that is, the solution overflows at the top of pipe 8 into said chamber 16 and falls down 80 pipe 19 and enters the bottom of the vacuum-pan 2 through valve 15. When valves 20 and 15 are opened and 21 is closed, the liquor will be carried from the bottom of the receiver 85 through the pump 7, piping 8, chamber 16, and piping 19 back to the bottom of the vacuum-pan. In this way a continuous circulation is maintained, which keeps the crystals in a state of suspension in a comparatively 90 small quantity of liquor and prevents clogging of any of the pipes. As the crystals accumulate the solution becomes heavier and 95 100

heavier, until it becomes desirable to draw it off into centrifugals or other suitable form of drier for extraction of the liquor from the crystals. For this purpose an exit is provided, as 5 at 10, which is adapted when open to permit the flow of the solution through pipe 9 to the centrifugals 12.

As before stated, pipe 8 extends upwardly to a considerable distance above the level of 10 the solution in the pan and empties into the upper part of the chamber 16, through which the solution falls into pipe 19 and is finally conducted through cock or valve 15 to the vacuum-pan. As a matter of fact, the solution stands 15 in pipe 19 at the same level as it stands in the vacuum-pan 2. The pipe 17, connecting the top of the chamber 16 with the vacuum-pan, maintains in said chamber the same vacuum-pressure as exists in the pan. Thus it will be 20 seen that the chamber 16 permits the liquor which circulates through pipe 8 overflowing at the top to descend pipe 19 to the level of the liquor in the pan without creating any increased suction on the column of liquor in 25 pipe 8. The pipe 8 should be of a sufficient height so that if there is a vacuum in the pan, and therefore in the chamber 16, of, say, twenty-six inches of mercury the weight of the column of liquor in 8 shall equal this 30 vacuum or it shall be sufficient to balance the suction of the pan, so that at a point above valve 10 the pressure of the column in the pipe 8 will be at least equal to atmospheric pressure. With these conditions existing 35 during the circulation, if valve 10 is open the liquor furnished by the pump will flow through it, liquor will cause overflowing at the top of pipe 8 into chamber 16, falling to a point which will just balance the vacuum. 40 The advantage of the arrangement is that any portion of the liquor may be withdrawn through valve 10 without allowing any air to enter the pan—that is, without danger of air being sucked back through valve 10 into 45 the vacuum-pan and without decreasing the amount of circulation through the pump and without increasing the pressure of the pump. By closing valve 10 and opening valve 21 the circulation may be maintained without going 50 through 16. If the pump were not running, the liquor would normally stand at the same level in pipes 8 and 19 as the level of the liquor in pan 2. It is therefore obvious that the pump merely has to lift the column of 55 liquor in pipe 8 the distance between the level of the liquor in the pan and the point of overflow of pipe 8 into chamber 16. As already stated, the purpose of the pump is to establish and maintain the circulation of the 60 crystal-bearing liquor, and thus prevent the clogging of the pipes, which is one of the greatest difficulties experienced in extracting crystals from a pan of this character.

The grinder 6 is provided upon the intake 65 side of the pump to protect the same by pul-

verizing large crystals and by crushing the scale which is apt to form on the tubes of the pan to prevent the same from clogging in the pump or the exit.

The pipe 14 connects the reservoir 13, which 70 receives the liquor flowing from the centrifugals 12, with the bottom of the vacuum-pan, so that said liquor may be drawn back into the pan upon the opening of valve 25 by the suction of said pan. Fresh solution for 75 evaporation may also be supplied to reservoir 13 and delivered to the pan in the same manner.

By the means above described I am able to 80 evaporate liquor under vacuum-pressure and to maintain a circulation of the crystals which form in the richer portion of said liquor by suspending said crystals in a minimum quantity of said richer liquor and circulating it past a valve-controlled exit-point. I am 85 thus enabled to maintain the evaporating process and arbitrarily withdraw from time to time the crystals without interfering with said continuous process of evaporation. I am also enabled to withdraw the crystals with a 90 minimum amount of liquor, whereas if the crystals were drawn directly from the pan without a circulation we should have clogging at one time and an excess of liquor at another time. 95

What I claim is—

1. As an improvement in the art of evaporating liquor, the step which consists in maintaining a circulation of the richer portion of the liquor. 100

2. As an improvement in the art of evaporating liquor, the step which consists in maintaining a circulation from and back to the richer portion of the bulk of liquor under treatment. 105

3. The process of evaporating liquor which consists in heating the liquor and maintaining a circulation of the richer portion thereof. 110

4. The process of evaporating liquor which consists in heating the liquor and maintaining a circulation from and back to the richer portion of the bulk of liquor being treated. 115

5. The process of evaporating liquor which consists in heating the liquor and maintaining a circulation from and back to the richer portion of the bulk of liquor being treated, and subjecting the liquor in circulation to the same pressure as that exerted on the bulk of liquor. 120

6. The process of evaporating liquor which consists in heating the liquor and maintaining a circulation from and back to the lower portion of the bulk of liquor being treated. 125

7. The process of evaporating liquor which consists in heating the liquor, maintaining a circulation from and back to the lower portion of the bulk of liquor being treated, and maintaining the same pressure on the circulating portion of the liquor as is maintained on the bulk. 130

8. The process of procuring crystals from liquor which consists in heating the liquor, collecting the crystals in one portion of the bulk of liquor and maintaining a circulation 5 of the crystal-bearing liquor. 60
9. The process of procuring crystals from liquor which consists in heating the liquor, collecting the crystals in one portion of the bulk of liquor, maintaining a circulation of 10 the crystal-bearing liquor, and controlling the size of the crystals being circulated. 65
10. The process of procuring crystals from liquor which consists in heating the liquor, collecting the crystals in one portion of the bulk of liquor, maintaining a circulation of 15 the crystal-bearing liquor, and separating the crystals therefrom. 70
11. The process of procuring crystals from liquor which consists in heating the liquor, 20 collecting the crystals in one portion of the bulk of liquor, maintaining a circulation of the crystal-bearing liquor, withdrawing the crystal-bearing liquor and separating the crystals therefrom. 75
12. The process of procuring crystals from liquor which consists in heating the liquor, collecting the crystals in one portion of the bulk of liquor, maintaining a circulation of the crystal-bearing liquor, controlling the size of 25 the crystals being circulated, and separating the crystals from the liquor. 80
13. The process of procuring crystals from liquor which consists in heating the liquor, collecting the crystals in one portion of the bulk of liquor, maintaining a circulation of the crystal-bearing liquor, controlling the size 30 of the crystals being circulated, withdrawing the crystal-bearing liquor and separating the crystals therefrom. 85
14. The process of evaporating liquor which consists in heating the liquor, reducing the pressure thereon and maintaining a circulation of the richer portion thereof. 90
15. The process of evaporating liquor which 45 consists in heating the liquor, reducing the pressure thereon and maintaining a circulation from and back to the richer portion of the bulk of liquor being treated. 95
16. The process of evaporating liquor which 50 consists in heating the liquor, reducing the pressure thereon and maintaining a circulation from and back to the richer portion of the bulk of liquor being treated, and subjecting the liquor in circulation to the same pressure as that exerted on the bulk of liquor. 100
17. The process of evaporating liquor which 55 consists in heating the liquor, reducing the pressure thereon, and maintaining a circulation from and back to the lower portion of the bulk of liquor being treated. 105
18. The process of evaporating liquor which consists in heating the liquor, reducing the pressure thereon, maintaining a circulation from and back to the lower portion of the bulk of liquor being treated, and maintaining the same pressure on the circulating portion of the liquor as is maintained on the bulk. 110
19. The process of procuring crystals from liquor which consists in heating the liquor, reducing the pressure on the liquor, collecting the crystals in one portion of the bulk of liquor and maintaining a circulation of the crystal-bearing liquor. 70
20. The process of procuring crystals from liquor which consists in heating the liquor, reducing the pressure on the liquor collecting the crystals in one portion of the bulk of liquor and maintaining a circulation of the crystal-bearing liquor and controlling the size of the crystals being circulated. 75
21. The process of procuring crystals from liquor which consists in heating the liquor, reducing the pressure on the liquor, collecting the crystals in one portion of the bulk of liquor and maintaining a circulation of the crystal-bearing liquor, and separating the crystals therefrom. 80
22. The process of procuring crystals from liquor which consists in heating the liquor, reducing the pressure on the liquor, collecting the crystals in one portion of the bulk of liquor, maintaining a circulation of the crystal-bearing liquor, withdrawing the crystal-bearing liquor and separating the crystals therefrom. 90
23. The process of procuring crystals from liquor which consists in heating the liquor, reducing the pressure on the liquor collecting the crystals in one portion of the bulk of liquor, maintaining a circulation of the crystal-bearing liquor controlling the size of the crystals being circulated and separating the crystals from the liquor. 100
24. The process of procuring crystals from liquor which consists in heating the liquor, reducing the pressure on the liquor collecting the crystals in one portion of the bulk of liquor, maintaining a circulation of the crystal-bearing liquor, controlling the size of the crystals being circulated, withdrawing the crystal-bearing liquor and separating the crystals therefrom. 105
